Specification for Design.

Patented Jan. 2, 1917.

Application filed January 29, 1916. Serial No. 75,182. Term of patent 14 years.

To all whom it may concern:

Be it known that I, JOHN A. HOEVELER, a citizen of the United States, residing at Chicago, in the county of Cook and State of Illinois, have invented a new, original, and ornamental Design for a Reflector, as shown, of which the following is a specification, reference being had to the accompanying drawings, forming a part thereof.

In the drawings, Figure 1 is a side elevation and Fig. 2 is a rear elevation taken at right-angles thereto.

I claim,—

The ornamental design for a reflector, as shown.

Signed at Chicago, in the county of Cook and State of Illinois, this 26th day of January, 1916.

JOHN A. HOEVELER.
